UNITED STATES PATENT OFFICE.

ALEXANDER FERDINAND VICTOR, OF DAVENPORT, IOWA.

PICTURE-PROJECTING MACHINE.

1,084,678.

Specification of Letters Patent.

Patented Jan. 20, 1914.

Application filed November 15, 1911. Serial No. 680,884.

To all whom it may concern:

Be it known that I, ALEXANDER FERDINAND VICTOR, a subject of the King of Sweden, (having declared his intention of 5 becoming a citizen of the United States,) residing at Davenport, in the county of Scott and State of Iowa, have invented new and useful Improvements in Picture-Projecting Machines, of which the following is 10 a full, clear, and exact description.

My invention relates to apparatus for projecting a picture through a lens on to a screen or curtain where the same is outlined on a greatly enlarged scale and the colors re- 15 produced with accuracy.

More particularly this invention pertains to apparatus for reflecting and projecting plain or colored post-cards and the like.

One of the objects of my invention is to 20 construct a machine of this character in such manner that the same is compact and neat in appearance, is easy to operate, and will not readily get out of order.

Another object is to provide means where- 25 by the illuminating agent or lamp may be carried by or contained in the body of the machine, thus obviating the necessity of an additional or separate part to be attached to or removed from the apparatus.

These and other objects I accomplish by 30 the means and in the manner hereinafter fully described and as more particularly pointed out in the claims, reference being had to the accompanying drawings forming 35 a part hereof.

In the drawings:—Figure 1 is a vertical side elevation of my improved projecting machine. Fig. 2 is a central longitudinal vertical section thereof. Fig. 3 is a frag- 40 mentary horizontal section taken on line 3—3, Fig. 1, looking in the direction of the arrows. Fig. 4 is a vertical longitudinal section, drawn to an enlarged scale, of one of the carbon-holders employed in connec- 45 tion with my improved machine, and Fig. 5 is an end elevation of said holder drawn to the same scale as Fig. 4.

The housing or casing of my invention consists of longitudinal sides, top and bot- 50 tom preferably made of select metal tubing 1, that is rectangular in cross-section, and

has its ends closed by cast metal plates 2 and 3. The tubing 1 is clamped between end-plates, 2 and 3, by top and bottom tie-rods 5 and 6, but the bottom tie-rods 6, extend 55 forward beyond the front end-plate and have their forward ends secured by screws to a vertical supporting-frame 18, for the outer stationary tube of the telescopic cylindrical lens-tube 17. The supporting-frame 60 18, and the rear end-plate 3 are provided with feet 4, which support the body of the housing or casing of the machine above the surface upon which the same rests, and thus provide for a circulation of air beneath the 65 same and enable the air to pass up through openings *a* in the bottom of the tubing 1. These bottom openings *a* may be covered if desired by a false bottom 30, which is raised above the bottom of the housing by down- 70 wardly turned integral lugs at its corners that constitute feet, and the upper surface of this false bottom is polished and assists in the reflection of the light furnished by the carbon-electrodes which will hereinafter 75 more fully appear.

The upper part of frame 18 is secured to and spaced from the front end-plate of the case by the rod 19, substantially as shown in Fig. 2 of the drawing, and it might be ob- 80 served, in passing, that the other tie-rods hereinbefore referred to are constructed similarly to rods 19.

The inner tube of the telescopic lens-tube is preferably provided at each end with suit- 85 able magnifying lenses, and the underside thereof is provided with a longitudinal downwardly extending rack 24, that projects through a longitudinal slot 23 in the lower portion of the outer tubular element of the 90 lens tube and is engaged by the pinion 25, mounted on spindle 26, which latter is journaled in suitable hangers or straps secured to and depending a suitable distance below the telescope. Slot 23 extends from frame 95 18, to end-plate 2, and when pinion 25 is turned in the direction desired by any suitable means, the inner tubular element of the lens-tube can be adjusted longitudinally to obtain the results sought for. 100

The rear plate 3 has its central area cut- away to provide an opening which is closed

by a suitable door 7, hinged along its lower edge to the bottom of said opening which is provided with a suitable latch 8, that engages the upper edge of said opening to retain the door in a closed position. About midway of the height of the door suitable card-clips 9, 9, of L-shaped cross-section, are soldered or otherwise secured to the inner surface of the door for the purpose of holding the card or picture while being exhibited.

The upper part of the front end-plate 2, between its upper edge and the telescopic lens-tube is provided with a transverse ridge or boss 10, the walls of which are pyramidal-shaped in cross-section, and the triangular ends α of which are arranged in planes at an angle of substantially forty-five degrees to the front wall of the housing. These ends α have suitable openings therein for the insertion therethrough of the reduced ends of carbon-holders 11. These holders 11 are substantially the same in construction, arrangement and operation as those illustrated and described in a companion application for Letters Patent of the United States for an improved electric arc-lamp, executed by even date herewith, filed November 15th, 1911, Serial Number 660,363 and preferably comprises a cylindrical-shaped body portion 12, that is made of fibrous insulating material. The holders are preferably hollow and have the exterior surfaces of their outer portions greater in diameter than their inner ends. A binding-post 14, is tapped radially into the outer portion of said holders, and a substantially V-shaped guide plate 15 is secured within the bore of said holders by means of the same screw or rivet γ that secures the binding-post in position. A leaf-spring 16 is mounted in the bore of the holder so that its free end will be normally in the crotch of said guide and when the carbon is inserted therein, said carbon will be frictionally held in position and can readily be rotated or adjusted circumferentially by hand. The relative position of the axes of the carbons is such that they converge toward each other and their point of intersection or arc-ing point is permanent and fixed, and, should the arc be formed on the side of the same farthest from the object being projected, said arc may be reversed and placed in proper relation to said object by simply rotating or turning the carbons on their own axes by hand.

When the arc is formed the light radiating therefrom will be thrown toward the object to be projected so that the latter will be brilliantly illuminated, and the rays of light will then be reflected through the lens from which they will be projected onto the screen in the usual manner. The light source being disposed above the plane of the top

of the pictures will not interfere with the projection of the same.

What I claim as new is:

1. In a display machine, an opaque housing provided with a metal front wall having an opening therein and which has an integral elongated pyramidal-shaped embossed panel adjacent said opening, a lens mounted in said opening, object-holders mounted on the rear wall of said housing, and a source of light carried by said housing comprising horizontally disposed carbons extending through the walls of said panel, which carbons are at a fixed point between said lens and holders and the light rays from which are thrown directly and uninterruptedly to the object-holder.

2. In a display machine, an opaque housing provided with a metal front wall having an opening therein and which has an integral elongated pyramidal-shaped embossed panel adjacent said opening, a lens mounted in said opening, object-holders mounted on the rear wall of said housing, and a source of light carried by said housing comprising horizontally disposed carbons the axes of which extend through the walls of said panel and converge toward each other and which are at a fixed point between said lens and holders.

3. In a display machine, an opaque housing provided with a metal front wall having an opening therein and which has an integral elongated pyramidal-shaped embossed panel adjacent said opening, a lens mounted in said opening, object-holders mounted on the rear wall of said housing, and a source of light carried by said housing comprising normally adjustable carbons extending through the ends of said panel that are at a fixed point between said lens and holders.

4. In a display machine, an opaque housing provided with a metal front wall having an opening therein and which has an integral elongated pyramidal-shaped embossed panel adjacent said opening, a lens mounted in said opening, object-holders mounted on the rear wall of said housing, and a source of light carried by said housing comprising normally adjustable carbons extending through the ends of said panel in a plane above the horizontal plane of projection of said lens and which are at a fixed point between said lens and holders.

5. In a display machine, an opaque housing provided with a metal front wall having an opening therein and which has an integral elongated pyramidal-shaped embossed panel adjacent said opening, a lens mounted in said opening, object-holders mounted on the rear wall of said housing, and a source of light carried by said housing comprising normally adjustable carbons extending through the ends of said panel, holders

mounted in the end walls of said panel the axes of which converge and are disposed in a horizontal plane, and carbons adjustably held in said holders that are at a fixed point between the vertical planes of said lens and said object-holders.

In witness whereof I have hereunto set

my hand this 26th day of September A. D. 1911.

ALEXANDER FERDINAND VICTOR.
